Primary Examiner — Catherine S Posthauer(57) **CLAIM**

The ornamental design for a dust proof lid with straw, as shown and described.

DESCRIPTION

FIG. 1 is a perspective view of a dust proof lid with straw showing my new design

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view with straw opened thereof of the dust proof lid with straw where the dust proof lid with straw is in an open state;

FIG. 9 is right side elevational view with straw opened thereof;

FIG. 10 is another perspective view with straw opened thereof; and,

FIG. 11 is another perspective view thereof.

The broken lines in the drawings depict portions of the dust proof lid with straw that form no part of the claimed design.
